UNITED STATES PATENT OFFICE.

CALVIN W. CAMP, OF CAMPTOWN, PENNSYLVANIA.

COMBINED TRUCK AND BAG-HOLDER.

SPECIFICATION forming part of Letters Patent No. 315,719, dated April 14, 1885.

Application filed October 13, 1884. (No model.)

To all whom it may concern:

Be it known that I, CALVIN W. CAMP, a citizen of the United States, residing at Camp-
town, in the county of Bradford and State of
Pennsylvania, have invented certain new and
useful Improvements in a Combined Truck and
Bag-Holder, of which the following is a speci-
fication, reference being had therein to the ac-
companying drawings.

10 This invention relates to a combined truck
and bag-holder, my object being to construct
the same so that it shall be simple, light, cheap,
and durable; and the invention consists in cer-
tain novel features hereinafter described, and
15 specifically pointed out in the claims.

Referring to the drawings, Figure 1 is a side
elevation, Fig. 2 a plan view, and Fig. 3 a
longitudinal section, of a combined truck and
bag-holder constructed in accordance with my
20 invention, and a detached perspective of the
bag-holding head j^3 . Fig. 4 is a detail of the
sliding table.

Like letters indicate like parts in all the
figures.

25 A represents a suitable bed or side rails, the
ends of which are extended to form handles A' .

To the rails A are secured slanting beams
A ^{2} , which rest upon the axle, and which are
30 connected with the side rails, A, by suitable
upright braces, A ^{3} A ^{4} . The frame-work thus
formed is provided with legs B. The wheels
C are journaled on the lower faces of the beams
A ^{2} at D.

E represents a sliding table having the usual
35 end board, E', said table being of such a width
as to fit in between the side rails, A.

To the under side of the table E is secured
a cleat, E ^{2} , which is chamfered, shouldered, or
40 cut away at both ends, as at E ^{2} , said cut-away
portions being adapted to fit longitudinal ribs
F, which are firmly secured to the inner faces
of the rails A, so that said table, with the aid
of suitable mechanism, hereinafter described,
is adapted to be raised and lowered.

45 Near the handles A' is journaled in the rails
A a roller or drum, G, one end of which is
provided with a crank, G', for the purpose of
turning the same. The roller G is also pro-
vided, it may be at either end, with a ratchet,
50 H, which is adapted to be engaged by a grav-
ity-pawl, H', whereby said roller may be held
in any desired position.

To the cleat or stop E ^{2} , for it may be called
either with equal propriety, is secured, by
any suitable means—in this instance by pass-
ing through a hole therein—a rope or chain, I,
the other end of which is secured to the drum
or roller G, whereby it is readily apparent
that by revolving said drum by means of the
crank G' the rope or chain will be wound
around the same and the sliding table elevated
to a desired height, and retained at said
height by means of the pawl H' engaging with
the ratchet H. The rope I may be extended
around a pulley in or on the cleat or stop E ^{2} ,
and to the fixed part of the frame-work near
the roller. (See dotted lines, Fig. 1.)

To the supports A ^{3} are secured spring-arms
J, which are pivoted by means of bolts J'.
Said supports are made vertically adjustable
70 for bags of different heights by means of holes
J ^{2} , through either of which the bolts J' may
be passed. To the upper ends of said arms
are secured heads J ^{3} , which are cut away, as
shown by dotted lines, Fig. 3, at J ^{4} , and which
75 may, or may not, as desired, be provided with
teeth or serrations, to enable the same to take
into the bag, but which serrations are not nec-
essary to the successful operation of the same,
as the resiliency of the arms tending to spread
80 them apart is sufficient to hold the mouth of
the bag X in position for filling, while its base
rests upon the board E'.

To limit the movement of the spring-arms,
both when their upper ends are swung out-
wardly to hold a bag in position for filling
and when released from the bag to prevent
the liability of their being strained by spring-
ing back, and also to serve as a support for
the same when out of position, as shown by
90 dotted lines, Fig. 1, I provide the guides K,
which may be secured in any suitable manner
to the frame-work of the truck. The wheels
C being located so that the slanting rails or
beams A ^{2} project beyond them, the truck, when
95 turned in a vertical position, stands firmly on
the ends of said beams A ^{2} and of the side rails,
A, as shown in Fig. 1, the dotted line repre-
senting a floor. Now, it will be seen that to
place a bag in position to be filled it is simply
100 necessary to turn the truck in a vertical posi-
tion, swing the upper ends of the arms out-
wardly, and spring the arms J toward each
other, so that the mouth of the bag may be

caught by the grippers or heads J^3 , said grippers being downwardly-projecting flanges formed by cutting away a portion of the heads J^3 , as above described. Then by releasing the 5 arms the bag X will be held, as shown in Figs. 1 and 2, with its mouth open, by reason of the tendency of the arms to spring apart at their upper ends. The bag being filled, the arms are released therefrom and spring back into their 10 normal position, the bag is tied and wheeled off to a wagon, or it may be an elevated platform, to be taken loaded into cars, when the sliding table is elevated by means of the crank G' , as shown by dotted lines, Fig. 3, and the 15 bag tilted off upon said wagon or platform, as the case may be. The ratchet being released, the sliding table will resume its normal position, the cleat or stop E^2 abutting against the tie-bar A^5 , and be ready for the next bag. If it 20 be desirable to use the truck simply as such, the spring-arms may be thrown out of position, as shown by dotted lines, Fig. 1. The sliding table, by being provided with only one cleat or stop, is capable of being withdrawn, the cleat 25 passing between the ends of the ribs and the roller, and the table can then be used for other purposes—such as, for example, a gang-plank, one end resting upon the roller G , and when entirely removed the truck is adapted for use 30 in moving barrels and similar packages.

No claim is herein laid to the construction of the truck or the sliding table, except in such features as co-operate with the spring-arms to constitute a combined truck and bag-holder.

35 When in a vertical position, the foot-board rests flatly upon the floor, and is therefore re-

lieved from solely supporting the weight of the bag and its contents, the arms J being adjustable to bags of varying heights when being filled.

I have hereinbefore stated that the bag is held by the grippers or heads J^3 with its mouth open. The grippers or heads are of such a width that when inserted within the bag its mouth is opened (see Fig. 3, the full lines 45 showing the bag X in section) sufficiently to permit the entrance of a scoop or measure, and to receive substances therefrom.

Having fully described my invention and its operation, what I claim, and desire to secure by Letters Patent, is—

1. The combination, with a truck, of spring bag-holding arms adjustably pivoted at opposite sides to the frame, substantially as specified.

2. The combination, with a truck, of spring bag-holding arms pivoted at opposite sides thereof, and guides for limiting the outward movement of said arms, and for retaining the same in contact with the sides of the framework of the truck, substantially as specified.

3. The combination, with the truck, of the spring-arms J , provided with the bag-holding heads or grippers J^3 J^4 , and apertures J^2 , the bolts J' , and the guides K , substantially as 65 shown and described.

In testimony whereof I affix my signature in presence of two witnesses.

CALVIN W. CAMP.
